TENNIS POST CAP

Brian Frederick Hirst, Halifax, England, assignor to
B. Hirst & Sons Limited

Filed Oct. 23, 1973, Ser. No. 408,566

Term of patent 14 years

Int. CL D25—01

U.S. CL. D28—1 C

-FIG. 1.-

-FIG. 4.-

-FIG. 2.-

-FIG. 5.-

-FIG. 6.-

FIG. 1 is an elevational view of a tennis post cap incorporating my new design.

FIG. 2 is a top plan view thereof.

FIG. 3 is a bottom plan view thereof.

FIG. 4 is an elevational view thereof taken at a right angle to the view of FIG. 1.

FIG. 5 is an elevational view of the side opposite that shown in FIG. 4.

FIG. 6 is a sectional view thereof taken on line VI—VI of FIG. 2.

The side opposite that shown in FIG. 1 is identical to the view shown.

I claim:

The ornamental design for a tennis post cap, substantially as shown and described.
